Claims priority, application Germany Dec. 21, 1956

11 Claims. (Cl. 200—93)

This invention is concerned with a polarized contact device comprising change-over contact means contained in a protective tubing.

A paper published in The Bell System Journal, November 1953, beginning on page 1393 describes a change-over contact contained in a protective tubing and polarized in predetermined manner by means of two exteriorly disposed magnets. In the corresponding structure, the ends of the outer contact springs, which project from the glass tubing, are provided with two permanent magnets, the magnetic circuit of these magnets being closed each over a flux guide sheet extending to the magnetically opposite end of the contact.

The present invention provides a structure which is, as compared with the known arrangement, very much simplified. The change-over contact structure according to the invention comprises a permanent magnet which brackets the outer contact springs, the field of the permanent magnet extending across the working air gap substantially transverse of the contact springs within a plane defined by the displacement of the change-over contact spring.

The advantage of the contact arrangement according to the invention resides among others in the possibility of using only one permanent magnet and elimination of flux guide means.

The various objects and features of the invention will appear from a description of embodiments which will be rendered below with reference to the accompanying drawing. In the drawing,

FIGS. 1, 2 and 3 show embodiments comprising a U-shaped permanent magnet;

FIGS. 4, 5 and 6 indicate an embodiment comprising a diametrically magnetized cylindrical body; and

FIG. 7 illustrates an arrangement for producing the premagnetization of the switch-over contact spring.

Referring now to FIGS. 1, 2 and 3, the permanent magnet may be made in the form of a U-shaped member having legs which embrace the protective tubing along an area in which is disposed the working air gap. The structure is shown in FIG. 1 in side view with some parts in section and in FIG. 2 in sectional view at the point of the working air gap. The protective tubing 1 contains the two outer contact springs 2 and 3 and the inner switch-over contact spring 4, such contact springs being made of magnetizable material. The U-shaped permanent magnet 5 is disposed at the area of the working air gap of the three contact springs. The polarization of the permanent magnet 5 is indicated by the letters N and S. Energizing coils 6 and 7 (FIG. 1) are provided for delivering the energy required for the actuation of the contact means.

The arrangement is based upon the following considerations:

The permanent magnet 5 produces in the working air gap a field whose forces are with proper adjustment equal between the switch-over contact spring 4 and the contact spring 2 and between the spring 4 and contact spring 3, respectively. The switch-over spring 4, accordingly, remains in its normal or resting position. If a further field is now produced by the energization of the coils 6 and 7, such field, depending upon its direction, will produce

2

amplification of the forces between the switch-over contact spring and one of the outer contact springs while weakening the forces between the switch-over contact spring and the other outer contact spring. Assuming sufficient strength of the field generated by the coils 6 and 7, the inner switch-over contact spring 4 will be attracted by one of the outer contact springs and will establish contact engagement therewith.

The above described arrangement offers the possibility of effecting an adjustment with simple means or affecting the operating time, respectively. For this purpose, the permanent magnet may be disposed rotatably about an axis extending perpendicular to the plane through the working air gap, which is defined by the motion of the switch-over contact spring. This plane is indicated in FIG. 2 by the dot-dash line.

FIG. 3 shows the structure according to the invention with the permanent magnet 5 in rotated position. A single energizing coil 8 may be employed, which will be sufficient provided that adequate energizing force is produced.

In the position of the permanent magnet 5, as illustrated in FIG. 3, there will be a stronger field between the contact springs 4 and 2 than between the springs 4 and 3, since one of the poles of the permanent magnet, the N-pole in the assumed case, is considerably closer to the contact spring 2 than the S-pole is to the contact spring 3. The permanent flux accordingly extends in this case from the N-pole to the end of the contact spring 2 and by way of the corresponding part of the working air gap to the contact spring 4, and thence at least partially as a stray flux directly to the S-pole, by-passing the contact spring 3. This one-sided amplification of the forces in the working air gap permits equalization of structural inaccuracies and in addition thereto, obtaining different operating times. In accordance with the illustrated position of the permanent magnet 5, a shorter time would be required for the actuation of the switch-over contact spring 4 in the direction of contact spring 2 than in the direction of contact spring 3.

Rotation of the permanent magnet 5 in opposite direction would produce corresponding but oppositely effective operations.

In the structures illustrated in FIGS. 1 to 3, the switch-over contact spring 4 assumes an intermediate position between the two outer contact springs 2 and 3. This structure presupposes a corresponding stiffness of the switch-over contact spring 4 and strength of the magnetic field produced by the permanent magnet 5. However, if the magnetic field is increased or the stiffness of the switch-over contact spring 4 is decreased, the latter will ultimately assume a position, referred to as flip-position, in which it is in engagement with one of the two outer contact springs 2 or 3. This operation is due to the fact that the course of the field produced by the permanent magnet is affected by the contact springs for, if the spacing between the switch-over contact spring and one of the outer contact springs is less than the space to the other outer contact spring, the field strength in the direction of the nearer outer contact spring will automatically increase, resulting in increase of the attractive force in the direction of the corresponding outer contact spring. In case of a symmetrical arrangement of the contact springs, both flip positions may be operative with respect to either one of the outer contact springs.

In accordance with another object and feature of the invention, there may be provided an embodiment comprising a permanent magnet in the form of a diametrically magnetized cylindrical body. Such an embodiment is shown in partially sectional side view in FIG. 4. FIG. 5 shows the corresponding structure in cross-sectional view along the working air gap. The permanent magnet

9 is of cylindrical shape and surrounds the protective tubing 1. The polarization of the polarized magnet is indicated by the letters N and S. About the permanent magnet 9 is disposed the energizing coil 10, which may be wound upon the permanent magnet or, if it is in the form of a separate coil, may be telescoped over the permanent magnet 9. The switch-over contact spring 4 is shown in a flipped position in which it is in contact-making engagement with the outer contact spring 2, having assumed this position responsive to the last preceding operative actuation. The change-over spring may be flipped into the alternate position, into contact-making engagement with the outer contact spring 3, responsive to subsequent energization of the coil 10, in which it will likewise remain, pending further energization of the coil 10.

For reasons of efficient production, the cylindrical permanent magnet 9 may be formed of a metal sheet, and in such case, there will result an axial slot as shown in FIG. 6, which may be of varying size. The slot should be of a width, such as will permit obtaining a diametrical magnetic field.

It is in accordance with the invention also possible to impart to the contact a preferential flip position. The switch-over contact spring may for this purpose be premagnetized; the premagnetization acting in a manner such, as if the energization coil would provide a predetermined permanent flux. Accordingly, the forces in the direction of one outer contact spring will be strengthened and in the direction of the other outer contact spring, they will be weakened.

FIG. 7 shows a suitable embodiment for producing the premagnetization of the switch-over contact spring. This embodiment comprises, as the one illustrated in FIG. 4, a cylindrical, diametrically magnetized permanent magnet 11, the field of such magnet extending across the working air gap transverse of the contact springs in a plane defined by the motion of the switch-over contact spring. A further axially magnetized cylindrical body 12 is placed about the protective tubing 1, such body surrounding the switch-over contact spring 4. In accordance with the polarization of the two permanent magnets, as indicated by the letters N and S, there will result a strengthening of the field between the switch-over contact spring 4 and the outer contact spring 2, and a weakening of the field in the direction of the contact spring 3, thereby imparting to the switch-over contact spring 4 a preferential flip position in which it will be in contact-making engagement with the contact spring 2. The energizing coil 13 is placed surrounding both permanent magnets 11 and 12. The energizing coil 13 may be caused to produce a field opposing the magnetization effected by the permanent magnet 12 and, assuming proper strength of such field, the flux direction with respect to the switch-over contact spring 4 will, accordingly, be reversed, causing such spring to be attracted by the outer contact spring 3 to assume contact-making engagement therewith.

It is, of course, possible to provide a place of the cylindrical permanent magnet, a permanent magnet of different configuration; for example, if desired, the switch-over contact spring as such may be made of permanent magnet material.

In conclusion, attention may be called to the possibility of rotating the permanent magnet, the field of which extends essentially transverse to the contact springs, about the longitudinal axis of the protective tubing. The result will be a shifting of the field in the working air gap, making it possible to equalize non-symmetries after assembling the parts.

Changes may be made within the scope and spirit of the appended claims.

We claim:

1. A polarized protective tubing change-over contact arrangement comprising an inner change-over contact spring made of magnetizable material and two outer con-

tact springs also made of magnetizable material, said outer springs cooperatively disposed relative to said inner contact spring and forming air gaps therewith, said change-over spring being movable in a path for selective contacting engagement with said outer contact springs, and a single permanent magnet having opposite poles bracketing both of said outer contact springs, the field of said permanent magnet extending across said air gaps of said contact springs substantially transverse thereof in a plane defined by the motion of a line disposed axially on said change-over contact spring.

2. A structure and cooperation of parts according to claim 1, wherein said permanent magnet is of cross-sectionally substantially U-shaped configuration.

3. A structure and cooperation of parts according to claim 1, wherein said permanent magnet consists of a diametrically magnetized cylindrical body.

4. A structure and cooperation of parts according to claim 1, wherein said change-over contact spring is premagnetized.

5. A structure and cooperation of parts according to claim 3, wherein said permanent magnet is axially slotted.

6. A structure and cooperation of parts according to claim 1, wherein said permanent magnet is disposed rotatable about an axis which extends through the air gaps perpendicular to the plane defined by the motion of said switch-over contact spring.

7. A structure and cooperation of parts according to claim 1, wherein said permanent magnet is disposed rotatable with respect to the longitudinal axis of the protective tubing for said contact springs.

8. A structure and cooperation of parts according to claim 1, comprising an energizing coil surrounding said permanent magnet.

9. A polarized protective tubing change-over contact arrangement comprising an inner change-over contact spring made of magnetizable material and two outer contact springs also made of magnetizable material, said outer springs cooperatively disposed relative to said inner contact spring and forming air gaps therewith, said change-over spring being movable in a path for selective contacting engagement with said outer contact springs, a single permanent magnet having opposite poles bracketing both of said outer contact springs, the field of said permanent magnet extending across said air gaps of said contact springs substantially transverse thereof in a plane defined by the motion of a line disposed axially on said change-over contact spring, and a further permanent magnet for effecting premagnetization of said change-over contact spring, said further permanent magnet being an axially magnetized cylindrical body surrounding said change-over contact spring.

10. A polarized protective tubing change-over contact arrangement comprising an inner change-over contact spring made of magnetizable material and two outer contact springs also made of magnetizable material, said outer springs cooperatively disposed relative to said inner contact spring and forming air gaps therewith, said change-over spring being movable in a path for selective contacting engagement with said outer contact springs, a single permanent magnet having opposite poles bracketing both of said outer contact springs, the field of said permanent magnet extending across said air gaps of said contact springs substantially transverse thereof in a plane defined by the motion of a line disposed axially on said change-over contact spring, and a further axially slotted permanent magnet formed by a cylindrical body surrounding said change-over contact spring whereby the latter is premagnetized.

11. A polarized protective tubing change-over contact arrangement comprising an inner change-over contact spring made of magnetizable material and two outer contact springs also made of magnetizable material, said outer springs cooperatively disposed relative to said inner contact spring and forming air gaps therewith, said

change-over spring being movable in a path for selective contacting engagement with said outer contact springs, a single permanent magnet having opposite poles bracketing both of said outer contact springs, the field of said permanent magnet extending across said air gaps of said contact springs substantially transverse thereof in a plane defined by the motion of a line disposed axially on said change-over contact spring, a further axially slotted cylindrical permanent magnet surrounding said change-over contact spring whereby the latter is premagnetized, and an energizing roll surrounding both said permanent magnets.
